To all whom it may concern:

Be it known that I, FERDINAND A. LOBERT, a citizen of the United States, residing at San Diego, in the county of San Diego and State of California, have invented certain new and useful Improvements in Composition for Pipes and Railroad-Ties; and I do declare the following to be a full, clear, and exact description of the invention, such as will enable others skilled in the art to which it appertains to make and use the same.

This invention relates to a composition of

matter especially designed for the manufacture of pipes and railway ties. 15

The object of the invention is to provide a composition of this character which will be indestructible by excessive heat or cold and will be water proof.

Another object is to provide a composition which will withstand a great amount of pressure.

The composition consists of the following ingredients combined in the proportions stated, to wit: 25

Rock asphaltum	1 ounce.
Karl asphaltum	1 ounce.
Marl	15 ounces.
Asbestos	½ ounce.
Sulfur	½ ounce.
Salt	1 ounce.
Seaweed	2 ounces.

These ingredients are combined, subjected to a gentle heat and thoroughly mixed after which the composition is placed in suitable molds in a plastic state and allowed to harden. Pipes, receptacles or other articles formed of this composition will not be affected by extreme heat or cold and will resist a pressure of 250 pounds to a square inch.

I claim as my invention:

35 A composition for pipes and railroad ties consisting of rock asphaltum, one ounce,

karl asphaltum, one ounce, marl, 15 ounces, asbestos, one-half ounce, sulfur, one-half ounce, salt, one ounce, seaweed, two ounces.

In testimony whereof I have hereunto set 40 my hand in presence of two subscribing witnesses.
